UNITED STATES PATENT OFFICE

148,247

DESIGN FOR A NURSERY CHAIR

Marie A. Kirkpatrick, Grand Rapids, Mich., assignor to Lullabye Furniture Corporation, Stevens Point, Wis., a corporation of Wisconsin

Application May 3, 1946, Serial No. 129,295

Term of patent 7 years

(Cl. D4—5)

To all whom it may concern:

Be it known that I, Marie A. Kirkpatrick, a citizen of the United States, residing at Grand Rapids, in the county of Kent and State of Michigan, have invented a new, original, and ornamental Design for a Nursery Chair, of which the following is a specification, reference being had to the accompanying drawing, forming part thereof.

The figure of the accompanying drawing is a perspective view of a nursery chair, showing my new design.

I claim:

The ornamental design for a nursery chair, as shown.

MARIE A. KIRKPATRICK.
